BEDSPREAD OR SIMILAR ARTICLE

Charles Shapiro, New York, N. Y., assignor to Shapiro & Son Curtain Corp., New York, N. Y., a corporation of New York

Application June 27, 1952, Serial No. 20,372

Term of patent 3½ years

(Cl. D92—2)

To all whom it may concern:

Be it known that I, Charles Shapiro, a citizen of the United States of America, residing at the city, county, and State of New York, have invented a new, original, and ornamental Design for a Bedspread or Similar Article, of which the following is a specification, reference being had to the accompanying drawing, forming part thereof.

In the drawing:

The figure is a plan view of a textile fabric showing the complete center and one fourth of the border of my new design. The other three corners bearing the same design are arranged in proper relation of the detailed illustration.

I claim:

The ornamental design for a bedspread or similar article, substantially as shown and described.

CHARLES SHAPIRO.
